HUMIDIFIER

Clifford W. Nesbitt, deceased, late of Albion, Mich., by Lena L. M. Nesbitt, administratrix, Albion, Mich.,
assignor to McGraw-Edison Company, Milwaukee,
Wis., a corporation of Delaware

Filed Dec. 1, 1960, Ser. No. 63,071

Term of patent 14 years

(Cl. D62—4)

Fig. 1

Fig. 3

FIG. 1 is a front perspective view of a humidifier embodying my new design; the rear, not shown, being substantially plain;

FIG. 2 is a right side elevation thereof; and
FIG. 3 is a top plan view thereof.

I claim:

The ornamental design for a humidifier, as shown and described.
